CLAIM

The ornamental design for a shelf as shown and described.

DESCRIPTION

FIG. 1 is a top, front, left perspective view of a shelf showing our new design in an illustrative environment mounted within an interior of a refrigerator/freezer; FIG. 2 is a top, front, right perspective view of a first embodiment of the shelf of FIG. 1; FIG. 3 is a top, front, right perspective view of the shelf of FIG. 2; FIG. 4 is a front elevation view of the shelf of FIG. 3; FIG. 5 is a back elevation view of the shelf of FIG. 3; FIG. 6 is a left elevation view of the shelf of FIG. 3; FIG. 7 is a right elevation view of the shelf of FIG. 3; FIG. 8 is a top plan view of the shelf of FIG. 3; FIG. 9 is a bottom elevation view of the shelf of FIG. 3; FIG. 10 is a top, front, right perspective view of a second embodiment of the shelf of FIG. 1; FIG. 11 is a top, front, right perspective view of the shelf of FIG. 10; FIG. 12 is a front elevation view of the shelf of FIG. 11; FIG. 13 is a back elevation view of the shelf of FIG. 11; FIG. 14 is a right elevation view of the shelf of FIG. 11; FIG. 15 is a left elevation view of the shelf of FIG. 11; FIG. 16 is a top plan view of the shelf of FIG. 11; and, FIG. 17 is a bottom elevation view of the shelf of FIG. 11. The broken lines in FIGS. 1, 2, 10, and 13-17 are included for the purpose of illustrating portions of the shelf or its environment that form no part of the claimed design.
